JUG OR SIMILAR ARTICLE

Livingston C. Douglas, Leonia, N.J., assignor to Colgate-Palmolive Company, New York, N.Y., a corporation of Delaware

Filed Jan. 22, 1962, Ser. No. 68,416

Term of patent 14 years

(Cl. D58—5)

Fig. 1

Fig. 2

Fig. 4

Fig. 3

*Fig.5**Fig.6*FIG. 1 is a top plan view of a jug embodying my new design, wherein the handle opening has a curved face with shallowly sculptured finger grooves and the shoulder is smoothly curved;

FIG. 2 is an end elevational view thereof;

FIG. 3 is a side elevational view thereof;

FIG. 4 is an end elevational view thereof; and

FIG. 5 is a side elevational view of a modified form of a jug embodying my new design, wherein the handle opening has a flat face with deeply sculptured finger grooves and the shoulder consists of a straight flat for-

ward section tapering downwardly at the point where the handle joins the body of the jug; and

FIG. 6 is a top plan view of the jug of FIG. 5.

I claim:

The ornamental design for a jug or similar article, as shown and described.
